CLAIM

The ornamental design for trouble light handle, as shown and described.

DESCRIPTION

FIG. 1 is a perspective view of the trouble light handle showing my new design;

FIG. 2 is a front view of the design for the trouble light handle;

FIG. 3 is a side view of the design for the trouble light handle;

FIG. 4 is a back view of the design for the trouble light handle;

FIG. 5 is a top view of the design for the trouble light handle; and,

FIG. 6 is a bottom view of the design for the trouble light handle.

The side opposite the side shown in FIG. 3 has the same appearance as shown in FIG. 3, but is the mirror image.
